UNITED STATES PATENT OFFICE.

JOSEPH W. LEWIS, OF WILKINSBURG, PENNSYLVANIA, ASSIGNOR TO WESTINGHOUSE ELECTRIC AND MANUFACTURING COMPANY, A CORPORATION OF PENNSYLVANIA.

MERCURY-VAPORE RECTIFIER.

1,078,629.

Specification of Letters Patent. Patented Nov. 18, 1913.

Application filed October 18, 1909. Serial No. 523,122.

To all whom it may concern:

Be it known that I, JOSEPH W. LEWIS, a citizen of the United States, and a resident of Wilkinsburg, in the county of Allegheny and State of Pennsylvania, have invented a new and useful Improvement in Mercury-Vapor Rectifiers, of which the following is a specification.

My invention relates to vapor electric apparatus, and particularly to the structures of such vapor rectifiers as are constructed of glass or other fragile material.

The object of my invention is to provide means for confining mercury or other liquid, which is vaporized in the operation of the device, to a small compartment or chamber within the rectifier bulb, in order that the device may be shipped and handled with a greater degree of safety than has heretofore been possible.

Mercury, which is ordinarily used in connection with vapor electric rectifiers, has a very high specific gravity, and, if allowed to flow freely within a relatively large glass bulb, it is liable to fracture the bulb in which it is contained unless extreme care is exercised.

According to my invention, I provide a funnel - shape partition, having an opening 30 large enough to permit the mercury vapor to circulate freely throughout the bulb but serving to hold the liquid mercury in one end of the bulb, irrespective of its position when the rectifier is not in operation.

The single figure of the accompanying drawing is a view, partially in section and partially in elevation, of a rectifier bulb constructed in accordance with my invention.

Referring to the drawing, the structure here shown comprises a bulb or receptacle of pear shape constructed of glass or other suitable insulating material, having a pair of protuberances 2 and 3 near its smaller end in which a direct-current terminal 4 and an auxiliary terminal 5 are respectively located, and a pair of alternating-current terminals 6 and 7 which are disposed in tubes 8 and 9 that extend into the bulb from its larger end, in the usual manner. The protuberances 2 and 3 are filled with mercury or other suitable liquid having similar characteristics, and a partition 10 is disposed

near the small end of the bulb 1 to hold the mercury in this end, irrespective of its position during shipment or handling of the rectifier, in order to prevent the fracture of the bulb. When the rectifier is once mounted in position for operation, it is not of material importance whether the partition 10 becomes fractured or destroyed by the operation of the device, and in fact, I prefer to construct it of thin, fragile glass in order to secure this result. It will be understood that the bulb is most likely to be destroyed in packing or in shipment before it is put into service, and any means for reducing the percentage of bulbs which are destroyed in transportation is particularly desirable, especially if such means can be provided without considerable expense.

I desire that modifications which do not depart from the spirit of my invention shall be included within its scope.

I claim as my invention:

1. In vapor electric apparatus, the combination with a glass tube or bulb having a conducting liquid disposed in one end, of a relatively thin, fragile glass partition of funnel shape, for confining the liquid to a small section of the bulb or tube during shipment, having an opening through which the vaporized liquid may pass freely to start the operation of the apparatus and adapted to be fractured by the continued operation of the apparatus.

2. In vapor electric apparatus, the combination with a glass tube or bulb having protuberances at one end and a conducting liquid disposed in the protuberances, of a relatively thin, fragile glass partition of funnel shape, for confining the liquid to a small section of the bulb or tube during shipment, having an opening through which the vaporized liquid may pass freely to start the operation of the apparatus and adapted to be fractured by the continued operation of the apparatus.

In testimony whereof, I have hereunto subscribed my name this 30th day of Sept., 1909.

JOSEPH W. LEWIS.
